CLAIM

The ornamental design for a hands free retractable pet leash, as shown and described.

DESCRIPTION

FIG. 1 is a front perspective view of a hands free retractable pet leash showing my new design;

FIG. 2 is a left side elevation view;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines shown in the drawings illustrate portions of the hands free retractable pet leash that form no part of the claimed design.

The dash-dot-dash lines in the drawings illustrate a boundary that forms no part of the claimed design.

1 Claim, 2 Drawing Sheets(56)
